WIRE-FEEDING MECHANISM

Roy W. Cummings, Beverly, Mass., assignor to
 United Shoe Machinery Corporation, Borough
 of Flemington, N. J., a corporation of New
 Jersey

Application April 3, 1939, Serial No. 265,638

6 Claims. (Cl. 140—125)

This invention relates to wire-feeding mechanism. The invention is herein illustrated as embodied in mechanism designed to serve as part of a machine for use in the manufacture of shoes for shaping uppers over lasts, as disclosed in a copending application of A. F. Pym, Serial No. 265,419, filed on April 1, 1939, but it is to be understood that it is more generally applicable to various uses.

In the machine shown in the above-mentioned application the wire-feeding mechanism serves, in the course of the operation of the machine on each shoe, to feed binder wire which is applied around the toe end of the shoe to hold the upper in lasted position. In such a machine it is important that the proper amount of wire be fed each time the wire-feeding mechanism is operated. An object of the present invention accordingly is to provide a construction such as to insure against any slippage of the feeding means on the wire. To this end, the construction herein shown comprises a pair of coaxial feed wheels arranged to grip the wire between opposed faces thereof, near their peripheries, a substantial distance about the axis of the wheels. To deflect the wire away from the wheels where it leaves them, a thin plate is located between the wheels to serve as a stripper; and in order to guard against excessive wear on this plate, the invention provides a construction in which the feed wheels are beveled so that their opposed wire-gripping faces diverge from each other toward the peripheries of the wheels, thus facilitating disengagement of the wire from the wheels by the action of the stripper thereon. Still further to insure the proper feeding of the wire, one of the wheels, in the construction herein shown, is provided with a series of teeth which grip the wire against the other wheel.

The novel features of the invention, including various novel details of construction and combinations of parts, will now be more particularly described with reference to the accompanying drawings and thereafter pointed out in the claims.

In the drawing,

Fig. 1 is a plan view, with parts broken away, of wire-feeding mechanism in which the invention is embodied;

Fig. 2 shows the mechanism in vertical section; and

Fig. 3 is a view, partly in elevation and partly in section, showing the feed wheels on an enlarged scale.

The drawing shows only as much of the wire-feeding mechanism included in the machine dis-

closed in the above-mentioned application as it is necessary to describe for an understanding of the present invention. The wire *w* is fed by a pair of coaxial feed wheels 2 and 4 supported by a casting 6 on which is secured a top plate 8. 5 This plate is recessed to receive the feed wheels and supports a shaft 10 which rotates with them, the shaft having an enlarged head 12 mounted in a bearing in the plate. The feed wheel 2 is provided with a sleeve 14 extending along the 10 shaft 10, and the wheel 4 with a sleeve 16 surrounding the sleeve 14. At their lower ends the two sleeves have slots 18 therein at opposite sides of the shaft 10, and into these slots extend tongues 20 formed on a member 22 which is clamped 15 against a shoulder on the shaft by a nut 24. The feed wheels, together with the shaft 10, are accordingly driven by the member 22. Bearing at its lower end against this member is a spring 26 which bears at its upper end against a collar 28 20 in engagement with the lower feed wheel 4. The spring, therefore, tends to force the lower feed wheel upwardly to grip the wire against the upper feed wheel 2, and it acts at the same time through the shaft 10 to support the wheel 2 25 against the upward pressure of the lower feed wheel by reason of engagement of a shoulder 30 on the head of the shaft with the top of the wheel 2.

The member 22 is driven by another member 32 30 rotatable in a bearing in the casting 6, the member 32 being held against axial movement by engagement of the casting with a shoulder 34 on the member and with a washer 36 confined by a beveled gear 38 fast on the lower end of the 35 member. In mesh with this gear is another beveled gear 40 keyed to a shaft 42 rotatable in the casting 6 and connected by a universal joint to another shaft 44. This shaft may be operated by means of the character disclosed in the previously mentioned application, but it is to be understood that the invention is not dependent upon the use of means of any particular character for rotating the feed wheels. In the construction shown the member 32 is rendered effective to operate the member 22 by the provision of intermeshing teeth 46 on the two members, these teeth having beveled side faces so that in the event of any obstruction to the feeding of the wire the teeth on the member 32 may slip over the teeth 50 on the member 22, the latter being forced upwardly against the resistance of the spring 26.

The wire is gripped between opposed faces of the feed wheels 2 and 4 adjacent to their peripheries, as illustrated at the right-hand side of Fig. 55

3. At the left-hand side of this figure, 48 designates the wire-gripping face of the wheel 2 and 50 the wire-gripping face of the wheel 4. The wire is conducted from a reel (not shown) through a bore 52 in an upwardly extending arm 54 of a member 56 and thence through a bore 58 (Fig. 1) in an arm 60 of this member which is in angular relation to the arm 54 and is secured in a slot formed in the plate 8. The bore 58 extends in substantially tangential relation to the peripheries of the feed wheels and its inner end is in the same plane as the opening between the wire-gripping faces of the wheels. The wire is confined in a curve between the feed wheels somewhat more than half way around the axis of the wheels by the plate 8, as illustrated in Fig. 1. To deflect the wire from between the wheels there is provided a thin plate 62 a portion of which is of annular form and lies between the wheels and another portion of which extends outwardly from between them, as shown in Fig. 1, to serve as a stripper for the wire. This outwardly extending portion is secured to the plate 8 and cooperates with the latter to provide a curved guideway 64 for the wire, this guideway being continued between a wall of the plate 8 and another plate 66 and leading toward means whereby the wire is utilized.

It will be understood that the stripper plate 62 is sufficiently thin to permit the wire to be properly gripped by the feed wheels and also to prevent undesirable friction between the wheels and the plate. In order to prevent excessive wear on the plate by reason of the contact of the wire therewith where the wire is deflected out from between the wheels, the wire-gripping portions of the wheels are so formed as to facilitate the disengagement of the wire from their gripping faces. As illustrated in Fig. 3, the wheels are beveled so that their wire-gripping faces 48 and 50 diverge from each other toward the peripheries of the wheels, thus making it comparatively easy for the stripper plate to deflect the wire outwardly. In the construction shown the wire-gripping face 48 of the wheel 2 is continuous all around the axis of the wheels, while the gripping face 50 of the wheel 4 is provided by a series of teeth 68 which engage the wire, thus affording still more effective insurance against slippage of the wheels on the wire.

It will thus be seen that the invention provides wire-feeding mechanism which, as compared with feed wheels arranged to grip the wire between peripheral faces thereof, affords greater insurance against slippage of the wheels on the wire under any conditions, by reason of the length of wire engaged by the wheels, the construction being such as to render it practicable to use coaxial feed wheels for the purpose in view without danger of excessive wear on the mechanism.

Having described the invention, what I claim as new and desire to secure by Letters Patent of the United States is:

1. In wire-feeding mechanism, a pair of coaxial feed wheels relatively movable axially and arranged to grip a wire between opposed faces thereof in a curve part way around their axis, and means for stripping the wire from the wheels, said feed wheels being formed to provide between

their wire-gripping faces an opening increasing in width toward the peripheries of the wheels to facilitate disengagement of the wire from the wheels by said stripping means.

2. In wire-feeding mechanism, a pair of coaxial feed wheels arranged to grip a wire between opposed faces thereof in a curve part way around their axis, and a stripper for engaging the wire between the wheels and deflecting it outwardly away from them, one at least of said feed wheels being beveled to provide a wire-gripping face diverging from the opposed face of the other wheel toward the peripheries of the wheels to facilitate deflection of the wire away from the wheels by said stripper.

3. In wire-feeding mechanism, a pair of coaxial feed wheels relatively movable axially and arranged to grip a wire between opposed faces thereof in a curve part way around their axis, a spring tending to effect relative axial movement of said wheels to cause them to grip the wire, and a stripper extending outwardly from between the wheels for deflecting the wire away from them, said feed wheels being formed to provide between their wire-gripping faces an opening increasing in width toward the peripheries of the wheels to facilitate deflection of the wire away from them by said stripper.

4. In wire-feeding mechanism, a pair of coaxial feed wheels relatively movable axially and arranged to grip a wire between opposed faces thereof in a curve part way around their axis, a spring tending to effect relative axial movement of said wheels to cause them to grip the wire, and means for stripping the wire from the wheels, one at least of said feed wheels being beveled to provide a wire-gripping face diverging from the opposed face of the other wheel toward the peripheries of the wheels and one of them having a series of teeth for engaging the wire.

5. In wire-feeding mechanism, a pair of coaxial feed wheels relatively movable axially and arranged to grip a wire between opposed faces thereof adjacent to their peripheries, means located opposite the peripheries of the wheels for confining the wire between them in a curve part way around their axis, and a stripper for disengaging the wire from the wheels beyond the region where it is thus confined, the wire-gripping faces of the wheels diverging from each other toward their peripheries to facilitate such disengagement of the wire therefrom.

6. In wire-feeding mechanism, a pair of coaxial feed wheels relatively movable axially and arranged to grip a wire between opposed faces thereof adjacent to their peripheries, means located opposite the peripheries of the wheels for confining the wire between them in a curve part way around their axis, and a stripper for disengaging the wire from the wheels beyond the region where it is thus confined, the wheels being beveled to provide between them a wire-receiving opening increasing in width toward their peripheries to facilitate disengagement of the wire from the wheels and one of them having a series of teeth for engaging the wire.

ROY W. CUMMINGS.
